CHARLES SCHIFFERLE, OF SAN FRANCISCO, CALIFORNIA, ASSIGNOR TO THE YUBA CONSTRUCTION COMPANY, OF SAN FRANCISCO, CALIFORNIA, A CORPORATION OF CALIFORNIA.

APPARATUS FOR SEPARATING MATERIALS OF DIFFERENT SPECIFIC GRAVITIES.

1,190,466.

Specification of Letters Patent. Patented July 11, 1916.

Application filed May 18, 1915. Serial No. 28,851.

To all whom it may concern:

Be it known that I, CHARLES SCHIFFERLE, a citizen of the United States, and a resident of the city and county of San Francisco, 5 State of California, have invented a certain new and useful Apparatus for Separating Materials of Different Specific Gravities, of which the following is a specification.

The invention relates to an apparatus for 10 separating materials of different specific gravities by displacing the materials of lesser specific gravity with the materials of greater specific gravity.

An object of the invention is to provide 15 an apparatus for separating materials of different specific gravities by displacing the lighter material with the heavier material.

Another object of the invention is to provide 20 an apparatus in which the displacement of the lighter material is accomplished by centrifugal force.

A further object of the invention is to provide 25 an apparatus in which the material to be separated is held in substantial equilibrium or in a mobile condition while being acted on by centrifugal force.

The invention possesses other advantageous features, some of which, with the foregoing, will be set forth at length in the following description where I shall outline in full that form of the apparatus of the invention which I have selected for illustration in the drawings accompanying and forming part of the present specification.

In the drawings, I have shown only one 35 specific form of the apparatus of my invention, but it is to be understood that I do not limit myself to such form, because my invention may be embodied in a multiplicity of forms, each being a species of my said invention.

It is also to be understood that by the claims succeeding the description of my invention I desire to cover the invention in 45 whatever form it may be embodied.

The invention is particularly designed to be employed in the concentration of crushed ores, placer sands and the like, to separate the greater specific gravity metal bearing 50 particles from the remainder of the ore, but it may be used in separating any mixture of particles of different specific gravities.

In accordance with my invention, the material to be separated is subjected to the action

of centrifugal force, while being maintained 55 in a loose or mobile condition or a condition of substantial equilibrium, so that the particles of greater specific gravity may pass through and displace the particles of lesser specific gravity. This is accomplished 60 by passing liquid or fluid into or through the material in a direction opposed to the direction of the centrifugal forces and the liquid or fluid forms a perfect mixture with the material, holding it in a loose condition 65 which permits the particles to arrange themselves in accordance with their specific gravities. The liquid or fluid is not flowed at such a rate that it carries off particles of 70 material of lesser specific gravity in suspension and the particles of lesser specific gravity are removed by being displaced by particles of greater specific gravity. The accumulated particles of greater specific gravity may then be removed in any desirable 75 manner. In dry separation, the material to be separated may be fed to the apparatus in a dry condition and air or other gas employed as the medium for maintaining it in a loose condition so that the particles are 80 free to move under the action of centrifugal force and in wet separation the material may be fed wet or dry, preferably wet and in solution, and the medium for maintaining it in a loose condition may be water or other 85 liquid.

In the accompanying drawings, in which I have shown one form of the apparatus of my invention, Figure 1 is a side elevation of the apparatus of my invention, parts thereof 90 being broken away to better disclose the apparatus. Fig. 2 is a vertical section of the apparatus shown in Fig. 1. Fig. 3 is a vertical section of a modified form of the apparatus, showing a form of concentration 95 discharge which may be employed.

The apparatus comprises an annular double walled casing 2, the outer and inner walls 3-4 thereof being substantially perpendicular, although the inner wall 4 may 100 flare outwardly very slightly as it progresses upwardly. The annular casing 2 is mounted on the hub 5, by suitable connecting means such as the hollow pan 6, which is formed integral with the casing. Secured to the hub 105 5 is a pulley 7 or other suitable means, by which rotary motion may be imparted to the hub and casing. The hub is rotatably

mounted on a suitably supported conduit 8 which is provided with apertures 9 within the hub. The hub is also provided with suitable apertures 12 opening into the hollow pan 6 to permit the passage of liquid or fluid from the hub to the casing. The liquid or fluid is introduced through the conduit and due to the action of centrifugal force is conveyed into the annular casing 2 completely filling the casing.

The inner wall of the casing is provided with one or more annular pockets 14-15 arranged above each other, the pockets being formed at the upper edge with a lip 16 which overlies and is spaced from an outwardly extending lip 17 on the inner wall. The space between the lips provides a passage for the liquid or fluid in the casing into the bottom of the pocket.

The material to be separated is fed onto the upper wall 18 of the pan 6 and is thrown outward to the edge of the pan and upward into the pockets in the casing. Liquid or fluid is introduced into the pan and casing in such amounts that it fills the pockets and discharges slowly therefrom. The material in the pocket is therefore saturated with liquid or fluid, which holds the particles apart and prevents them from packing, which results in practically holding the particles in suspension so that they are free to arrange themselves under the action of the centrifugal force. The particles of greater specific gravity are driven to the bottom of the pocket, displacing the particles of lesser specific gravity. When sufficient material has been fed to completely fill the lowermost pocket, the heavier particles of the subsequently fed material dis-

place the lighter particles in the pocket and the lighter particles travel upward into the next pocket above. When the lower pocket has completely filled with the heavier particles and additional heavier particles are fed, the heavier particles lodge in the second pocket, crowding out the lighter particles which pass into the next pocket above. As many superposed pockets may be arranged as desired. The particles of lesser specific

gravity pass over the upper edge of the casing and discharge into the receiver 19 which is provided with a sloping bottom 21 and a discharge conduit 22. The particles of greater specific gravity accumulate in the pockets and when these are fully charged with the heavier particles the feed of material is stopped and the rotating casing stopped and the heavier particles removed.

The particles in the pockets during the operation of the apparatus being held in a substantial state of suspension or equilibrium in the liquid or fluid, move laterally with relation to each other on account of the rotation of the casing and this lateral movement assists in releasing the particles, so

that the particles of greater specific gravity may move radially to the bottom of the pocket. It is understood that during the operation of the apparatus fluid or liquid is moving slowly inward through the material in the pocket, but the separation of the particles is accomplished by displacement and not by the carrying effect of the fluid or liquid.

In Fig. 3, I have shown a form of apparatus in which only one annular pocket 23 is provided and in which means are provided for discharging the accumulated particles of greater specific gravity from the pocket during the operation of the apparatus. The pocket 23 is provided at spaced intervals with discharge conduits 24, extending through the outer wall 3 of the casing. Each conduit 24 is provided with a valve, the head 25 of which is adapted to seat on and close the conduit and the stem 26 of which is supported and guided in the conduit. Surrounding the casing is a stationary cam 28 which engages the heads of the valves. The cam is offset at one portion so that the valves at that portion are moved outward from their seats, opening the discharge conduit and allowing the accumulated particles of greater specific gravity to discharge into the surrounding receiver 27. At its other portion the cam is concentric with the casing and arranged to hold the valves seated. On account of the loose state of the material in the pocket, the accumulated heavier particles quickly redistribute themselves when some of them are discharged at one place, thereby obviating the necessity of providing discharge conduits at all points on the pocket.

By the use of this apparatus, concentration or separation of particles of different specific gravities may be quickly and efficiently accomplished. When the particles of greater specific gravity are of such material, such as gold or silver, that will readily amalgamate, a quantity of mercury may be introduced into the pockets and the separation thereby made more efficient.

I claim:

1. An apparatus of the character described, comprising a rotatable annular casing, means for introducing fluid into said casing to fill the same, an annular pocket formed in the inner wall of said casing and a lip on the casing extending into said pocket, the lip being spaced from the wall of the pocket to permit fluid to flow from the casing into the pocket.

2. An apparatus of the character described comprising a rotatable annular casing, means for introducing fluid into said casing to fill the same, an annular pocket formed in the inner wall of said casing, said inner wall being provided with an annular slot for conveying fluid from the casing to

- the bottom of the pocket, a discharge outlet for said pocket, a valve controlling said outlet and means for operating said valve.
3. An apparatus of the character described comprising a rotatable annular casing, means for introducing fluid into said casing to fill the same, an annular pocket formed in the inner wall of said casing, said inner wall being provided with an annular slot for conveying fluid from the casing to the bottom of the pocket, a discharge outlet for said pocket, a valve controlling said outlet and means operative by the rotation of the casing for operating said valve.
4. An apparatus of the character described comprising a rotatable annular casing, means for introducing fluid into said casing to fill the same, an annular pocket formed in the inner wall of said casing, said inner wall being provided with an annular slot for conveying fluid from the casing to the bottom of the pocket, a discharge out-
- 5
- 10
- 15
- 20

let for said pocket, a valve controlling said outlet, means for operating said valve to discharge material in the pocket and a receptacle adapted to receive said discharged material.

5. An apparatus of the character described comprising a rotatable annular casing, means for introducing fluid into said casing to fill the same, an annular pocket formed in the inner wall of said casing, means for conveying fluid from the casing to the bottom of the pocket, a discharge outlet for said pocket, a valve controlling said outlet projecting beyond the casing and a stationary cam surrounding the casing and engaging said valve.

In testimony whereof, I have hereunto set my hand at San Francisco, California, this 40
6th day of May, 1915.

CHARLES SCHIFFERLE.
